ORNAMENTAL WHEEL DISK STRUCTURE

George Albert Lyon, Allenhurst, N. J.

Application December 19, 1934, Serial No. 758,178

7 Claims. (Cl. 301—37)

My present invention relates to an ornamental wheel disk structure, and more specifically to an ornamental disk and wheel structure wherein the disk may be snapped into and out of engagement with spring elements carried by the wheel, the disk being of such configuration and width as to conceal all of the exposed surface of the wheel flange which is connected to the rim, and also to take the place of the usual hub cap.

10 An object of the invention relates to the formation of the center of the disk with an outwardly depressed circular portion which not only simulates a hub cap, but which lends itself readily to cooperation with spring elements for retaining the disk in position on the wheel.

Another and further object of the invention relates to the provision of an ornamental disk wheel structure wherein the wheel has a plurality of centrally positioned spring elements so arranged that they will readily and tightly embrace a central portion of a disk snapped thereover, and will at the same time provide strength where the spring elements bear upon the disk.

In accordance with the general features of the invention, there are provided herein two embodiments of the invention, in each of which there is an ornamental disk of relatively thin metallic sheet material, having a cushion at its outer margin for engagement with the wheel rim, and having a central outwardly depressed portion which lends itself to ornamentation for causing it to simulate a hub cap, and which depressed portion is cooperable with a plurality of spring elements secured to the wheel flange or hub part; these elements being so arranged as to be cooperable with the central portion of the disk in such a manner that strength is provided in the resulting structure where the disk is engaged by the spring elements.

40 Another feature of the invention is the location of the cushioned outer portion of the disk with respect to the wheel rim so that any tendency of the disk to shift up or down is resisted by the cushioned bearing of the disk on the rim.

45 Other objects and features of this invention will more fully appear from the following detailed description, taken in connection with the accompany drawings, which illustrate several embodiments thereof, and in which:

Figure 1 is a front view of an ornamental wheel disk structure embodying the features of this invention; Figure 2 is an enlarged fragmentary sectional view taken on line II—II of Fig. 1; Figure 3 is a side view of a modified structure;

and Figure 4 is an enlarged fragmentary sectional view taken on the line IV—IV of Figure 3.

As shown on the drawings:

The reference numeral 9 designates generally a drop center wheel rim which includes a base 5 flange 10, opposite intermediate flanges 11, and turned edges 12. Secured to the base flange 10 is a body part 13 which has an inwardly turned outer margin 14 secured by any suitable means such, for example, as rivets 15 to the base flange 10 10 of the wheel rim.

As I have indicated by the reference character 16 there is an annular joint or groove in the outer side of the wheel which is disadvantageous from an ornamental standpoint in that it is a 15 dirt collector and also in that it interrupts the continuity of the outer appearance of the wheel. It is to cover this joint as well as the entire part 13 that I have provided a novel disk 25 which I will describe more in detail hereinafter. 20

The body part 13 of the wheel has an inwardly depressed fastening part 17 which is adapted to be secured by the usual bolts or cap screws 18 to a vehicle hub 19 to which may be attached a brake drum 20 in the usual way. 25 Since the bolts 18 must be accessible for removal or application to the wheel, the disk 25 embodying the features of this invention must also be removable whenever it is desired to get to the 30

The body part 13 of the wheel has secured to it a plurality of disk retaining spring elements 21 each of which has one end offset laterally as indicated at 22 to be secured to the part 13 by any suitable means such for example as the rivets 35 23. The external or free end of each of the elements 21 is bent outwardly as indicated at 24 for cooperation with the inclined side 26 of an outwardly pressed portion 27 disposed centrally of the disk 25. 40

This outwardly pressed central portion 27 of the disk 25 is shaped to simulate a hub cap and lend itself readily to ornamentation. I have illustrated this portion 27 as being provided with an outer thin metallic shell 28 having its outer 45 edge rolled at 29 about the edge of the out-pressed portion 27. This shell 28 may have any suitable indicia thereon such, for example, the name of the automobile to which the wheel is applied, or the trade-mark or any other insignia 50 such as is commonly used on hub caps.

The outer portion of the disk is turned as indicated at 30 so as to form an annular groove into which a smaller tube 31 of a double tube cushioning element may be compressed. The larger tube 55

32 of this cushioning element is adapted to tightly engage the surface of the wheel rim adjacent to the base flange 10 as is clearly shown in Figure 2. The cushioning element may be made of any 5 suitable material such, for example, as soft rubber, and is illustrated as having a cross-sectional shape resembling a numeral 8. Moreover, this cushioning element is preferably in the form of a split ring and is adapted to be progressively pressed into the groove provided by 10 the turned edge 30 of the disk 25. Also the smaller tube 31 of this cushioning element may have in it a wire ring 33 cooperable with the cushioning element to aid in maintaining it in the groove in the outer periphery of the disk. 15 I have also illustrated at 35 a prying tool such, for example, as a screw driver for prying loose the disk from the wheel. This tool is adapted to engage the turned edge 30 of the disk and to bear against the outer intermediate flange 11 of 20 the wheel rim. The location of the edge 30 of the disk is such that the prying tool can bear on the intermediate flange 11 as a fulcrum point in the operation of prying the disk from the 25 wheel. This feature is advantageous in that it provides enough clearance between the tool and the tire which may be mounted on the wheel to allow the tool to be used as a lever. Upon a slight pressure being applied to this tool, the disk 30 is easily pried loose from the spring retaining elements 21.

Of course, when the disk is in position on the spring retaining elements 21, these elements are under compression and tend to hold the disk 35 with its outer cushioning bead tightly against the wheel rim. Also, the edge of the disk is so located with reference to the wheel rim that any tendency of the disk to shift up and down is substantially resisted by the cushioned engagement of the wheel rim.

The disk 25 may be finished in any suitable color to blend with any other colors used in the automotive vehicle and this finishing of the disk should take place prior to the clinching of the 45 ornamental hub cap plate 28 to the portion 21 of the disk.

From the foregoing, it will of course be evident that the structure that I have provided is light in weight, easy to manufacture and has relatively great strength where the spring elements 50 bear upon the disc. Moreover, much stronger spring elements than those illustrated could be employed if necessary without resulting in any damage or distortion in the disk.

55 In Figures 3 and 4 I have illustrated a modification of the invention in which the same numerals have been employed to designate parts of the wheel which are identical with parts of the wheel shown in the first form of the invention. No description of these parts which are the same is thought to be necessary.

In this form of the invention the disk 25' is held in cooperation with the wheel by means of a plurality of spring elements which, as in the 65 case of the spring elements 21, may be five in number. Each of these elements 21' has a leg 22' secured as by means of rivets 23' to the body part 13. The outer or free end of the spring element 21', instead of being bent outwardly, is 70 bent into the shape of a hook, as indicated at 24', for bearing against the inclined surface 26' of the portion 27' of the disk. This portion 27', as in the case of the preferred form of the invention, has clinched to it an insignia plate or 75 shell 28' which may be made of light metal and

have ornamentations thereon similar to that usually employed on a hub cap. The spring elements, when the disk is shoved axially into cooperation therewith, as in the case of the preferred form of the invention, are cammed inwardly until they are in engagement with the inclined surface 26' of the disk. These spring elements, when thus engaged, are under compression and hold the disk tightly against the rim 19. 10

This form of the disk is also provided with a turned outer edge 30' which carries a rubber cushioning means 31' similar to the one described in the preferred form of the invention. In addition thereto, the outer portion of the disk 25' 15 has an ornamental bead 40. This bead 40 is of a curved cross-sectional shape, and is rolled or spun over the outer edge of the disk so as to become a part of the disk. Also, this band or bead 40 may be given a lustrous metallic finish, 20 such, for example, as a nickel or chromium plate, thereby enhancing the appearance of the ornamental disk.

It should also be noted that in this form of the disk the portion thereof between the central portion 27' and the cushioned outer edge is bulged outwardly instead of inwardly as in the case of the previously described form of the invention. 25

In both forms of the invention, the body part 30 13 may be made solid or, if it is so desired, this part 13 may be apertured so as to cause it to simulate spokes as is quite often done in the manufacture of wheels of the present character.

From the foregoing description, of two forms 35 of my invention, it will be noted that in each form the disk 25-25' proper comprises a single piece of material which extends radially outward to the wheel rim, and which includes as a portion of it a part which takes the place of the usual 40 hub cap which is used at present with the conventional wheel. This hub cap portion 21-21' of both forms of the invention is so formed as to cooperate with concealed spring elements carried by the wheel when the disk is pressed against 45 the flanged surface of the wheel rim. That is to say, upon the cushioned outer edge of the disk being pressed against the flanged surface of the wheel rim, the free ends of the spring elements are forced over a central turned edge of the disk, 50 so as to exert pressure against the inclined portion 26-26' of the disk. By thus exerting this pressure against the inclined surface of the disk, the disk is in reality pressed inwardly by the spring elements tightly against the flanged surface of the rim. Thus the disk is not only cushioned on the wheel, but the cushioned engagement is maintained by reason of the pressure exerted upon the disk by the spring retaining elements 21-21'. 55

Attention is also directed to the fact that, while I have illustrated that the disk is of such a diameter as to have its outer edge disposed inside of the valve stem opening 60 in the wheel rim, still it is within the scope of my invention to 65 use a disk of a larger diameter and to notch or slot it out so as to allow the valve stem to extend through the opening of the slotted or notched portion.

Then, too, the disk of my invention may be 70 given any suitable contour or configuration which may be desired by the automobile manufacturer to cause the wheel to be in keeping with other appointments of the vehicle, without changing the shape or construction of the wheel. This is 75

obviously advantageous, since heretofore, every time a change in the shape or design of the wheel was made, new dies and equipment had to be used in the wheel building apparatus.

5 The disk of my invention may be easily and inexpensively spun or blanked from relatively thin metallic sheet, and may thereafter be delivered unfinished to the automobile manufacturer, so that it may be finished at the same time as 10 other parts of the automobile with which it is to harmonize in color and appearance.

I am aware that many changes may be made and numerous details of construction may be varied through a wide range without departing from 15 the principles of this invention, and I, therefore, do not purpose limiting the patent granted hereon otherwise than necessitated by the prior art and the scope of the appended claims.

I claim as my invention:

20 1. The combination with a wheel including rim and body parts, of an ornamental wheel disk for disposition on the outer side of the wheel having an intermediate generally radially inwardly directed annular reentrant portion, and a plurality 25 of spring elements secured to an outer surface of the body part and projecting axially beyond the dimensions of the body part, each of said elements being substantially parallel to the axis of the wheel and having free ends over which 30 said reentrant portion of the disk is adapted to be cammed so that the disk may be retained in position on the wheel solely by said elements with said disk contacting only said elements and a radially outwardly spaced portion of said wheel.

35 2. An ornamental wheel disk for disposition on the outer side surface of a vehicle wheel in contact with a radially outer part of the wheel, said disk being made of relatively thin sheet material and having a bulged central part connected 40 by an inwardly converging conical wall with the remainder of the disk, and a shell intimately disposed over said central portion and clinched over a part of said wall, said wall also being shaped to afford an inner surface for engagement by 45 retaining means carried by the wheel.

3: In combination, a vehicle wheel carrying spring retaining means, and an ornamental disk arranged for snap-on engagement with said retaining means and for engagement with a pry- 50 off tool to remove the disk from the wheel, said disk being formed of sheet material having a bulged central part connected with the remainder of the disk by an inwardly converging conical wall which provides a face for engagement by said retaining means, a shell intimately overlying said central part and clinched over said wall, and decorative means providing an added thickness of material where said disk is engaged by the pry-off tool.

60 4. The combination with a wheel including a wheel mounting portion, an axial portion extending generally axially from said mounting flange, a body member extending from the outer end of said axial portion, and a rim part, of an ornamental disk member for disposition on the side surface of a wheel, said disk member being constructed to contact the wheel in proximity to the

wheel body member's outer periphery and spaced from the remainder of the wheel, and axially extending resilient means on one of said members for snap-on engagement with the other of said members in the region of the junction of 5 said axial portion and said body part, said means affording the sole means of attachment for said disk member and being of sufficient length to hold said disk member on the wheel in contact with an outer part of the wheel. 10

5. The combination with a wheel including a wheel mounting portion, an axial portion extending generally axially from said mounting flange, a body member extending from the outer end of 15 said axial portion, and a rim part, of an ornamental disk member for disposition on the side surface of the wheel, said disk member being shaped to contact the rim part of the wheel and being spaced from the remainder of the wheel, and axially extending resilient means on one of 20 said members for snap-on engagement with the other of said members in the region of the junction of said axial portion and said body part, said means affording the sole means of attachment for said disk member and being of sufficient length 25 to hold said disk member on the wheel in contact with said rim part, and said disk part terminating between lateral rim flanges in a manner to permit a prying tool to be inserted between the peripheral margin of the disk and the rim 30 and fulcrumed against a rim flange. 35

6. The combination with a wheel including a wheel mounting portion, an axial portion extending generally axially from said mounting flange, a body member extending from the outer end 35 of said axial portion, and a rim part, of an ornamental disk member for disposition on the side surface of the wheel, said disk member being shaped to contact the rim part of the wheel and being spaced from the remainder of the wheel, 40 and axially extending resilient means on one of said members for snap-on engagement with the other of said members in the region of the junction of said axial portion and said body part, said means affording the sole means of attachment 45 for said disk member and being of sufficient length to hold said disk member on the wheel in contact with said rim part, and means associated with the outer margin of the disk member to thicken the construction in this region 50 to withstand repeated use of a prying tool. 55

7. An ornamental wheel disk for disposition on the outer side of a wheel, said disk being of relatively thin sheet material and of a size to cover a substantial part of the outer side of the wheel, 60 the outer portion of the disk being provided with means for yieldably engaging the wheel, and the central portion of the disk being provided with an outwardly pressed central portion of a configuration corresponding to that of a hub cap and having secured to it an ornamental shell the central portion of which simulates a hub cap, said central portion merging into an inwardly converging conical wall portion to define on its inner side a spring-engaging surface. 65

GEORGE ALBERT LYON.
